UNITED STATES PATENT OFFICE.

FREDÉRIC A. BERNE, OF BIRMINGHAM, ALABAMA, ASSIGNOR TO SOUTHERN FERRO-CONCRETE COMPANY, OF ATLANTA, GEORGIA, A CORPORATION OF GEORGIA.

TRAIN-SHED.

No. 910,776.

Specification of Letters Patent.

Patented Jan. 26, 1909.

Application filed July 10, 1907. Serial No. 383,111.

To all whom it may concern:

Be it known that I, FRÉDÉRIC A. BERNE, a citizen of France, residing at Birmingham, in the county of Jefferson and State of Alabama, have invented new and useful Improvements in Train-Sheds, of which the following is a specification.

My invention relates to improvements in train sheds and similar structures designed particularly with reference to providing a structure, built on the unit plan and therefore capable of extension in any direction, which possesses the advantage of perfect ventilation, ample light, and an extremely low cost of construction and maintenance.

The principle of construction, upon which my invention is based, involves the provision of a series of parallel lower decks which cover the train platforms between tracks and upper decks which cover the tracks and overlap the lower decks so as to leave ample space for the escape of smoke and admission of light while preventing rain, smoke, etc., gaining access to the platforms. According to this construction the upper decks are supported above the lower decks and so positioned as to provide lateral protected ventilating and light admitting openings which parallel the tracks and are distributed throughout the shed at points where they will best serve to light the relatively low structure and free it of all smoke and gases.

According to my preferred construction, the lower decks are each supported at the center by a single row of columns and act on the principle of cantilevers to support from their side edges the upper decks. It is also an important point of construction that the underface of the upper decks which are disposed above the tracks should slant upwardly to each side, or, in other words, form deflecting surfaces for the purpose of directing the smoke and gases from the locomotives towards the adjacent lateral ventilating openings on either or both sides.

My invention also involves certain features of importance in connection with the drainage of such sheds, particularly when constructed from reinforced concrete.

My invention also involves other points in the construction and arrangement of parts which are hereinafter more fully described and claimed and which are also illustrated in the accompanying drawings forming a part of this specification, and in which:

Figure 1, represents a vertical cross-sectional view of my improved shed. Fig. 2, represents a vertical sectional view along the line $x-x$ of Fig. 1.

Similar reference numerals refer to similar parts throughout the drawings.

I have illustrated my invention in a train shed constructed from reinforced concrete. Obviously, however, this is but illustrative as any other material may be used and the principles of construction involved may be adapted to various other structures.

Referring to the drawings, the platforms 1, between the tracks 2, are covered by the lower or platform decks 3 of the shed. These decks are formed of thin reinforced concrete and are supported at intervals by cantilever beams 4 which are formed of strongly reinforced concrete and supported at their centers by columns 5. The side edges of the decks 3 have vertical side walls 6 which project upwardly. The beams or arches 7 which support the upper decks 8 rest upon the ends of the cantilever beams 4, each upper deck being thus supported by the two adjacent lower decks and disposed so as to completely cover the open space between said lower decks and above the track or tracks laid between the platforms covered by said lower decks. In the construction shown these beams are formed of reinforced concrete and are spaced any desired distance apart.

By referring to Fig. 2, it will be seen that a longitudinal ventilation and light opening 9 is formed between the top of each side wall 6, and the overhanging side edge of the superimposed upper deck. This opening is calculated to permit free egress to the smoke and admit sufficient light. Also the overhang of the upper decks are calculated with reference to the top of the adjacent side walls 6 to prevent rain or snow being blown in through the openings 9. I thus provide a relatively low structure which considered transversely presents a series of alternate upper and lower overlapping decks with longitudinal protected lighting and ventilating apertures between the overlapping edges of upper and lower decks, and this I consider broadly novel for the purposes contemplated by my invention. The upper decks 8 have their underfaces sloping upwardly and outwardly from a center line to the side edges, which overlap the side edges of the adjacent lower decks. To further brace and strengthen

the structure, the adjacent upper decks are connected by cross-braces 10. It will be seen that the lower decks, supported each by a single row of columns, serve as cantalivers to support the upper decks, thereby giving a structure which presents a minimum interference to platform traffic. Broadly considered, however, the upper decks may be supported in other ways, that described 10 being only preferred construction.

In practice, the side edges of the lower decks should be below the top of the smoke stack of the locomotives to prevent the smoke being deflected towards the platforms. 15 The slope or angular disposition of the under-face of the upper decks serves to deflect the smoke as well as the cinders from the locomotives through the openings 9.

In structures of this character which are 20 built upon the unit system and therefore liable to be extended over a considerable area, the matter of drainage becomes one of considerable importance:

It is my purpose to so drain the shed as to 25 avoid any large accumulation of water at any drainage point. To this end I make the upper decks so that they drain towards the center and I provide a series of conduits 11 formed in the beams 7 and leading from 30 the center line of each upper deck down through the beams to discharge upon the lower decks which in turn are drained by conduits 12 leading down through the decks 3, cantalivers 4 and their supporting columns 5 to a drain pipe 13 below each platform and running lengthwise thereof. I 35 prefer to arch the sections of the decks between their supporting beams 4 and 7, as seen in Fig. 2.

40 In Fig. 1, I show the shed with the decks designed for single and double tracks. Obviously the side edge of the outside upper decks will receive appropriate supports until it is desired to add another platform or platform 45 forms and extend the shed laterally to cover them when any desired number of upper and lower decks may be added. Also the shed may be longitudinally extended at will as it is, as a whole, entirely independent of 50 any unity of design and structure. It is in fact a sectional or unit system of overlapping upper and lower decks which provide a covered and protected shed which is better lighted and ventilated than the vast structures now in use and is also free from the 55 many serious objections which practice has shown to exist with regard to such structures.

A feature of considerable importance in 60 my invention is the use of concrete throughout the shed structure thereby eliminating all exposed metals which are injured by the gases from the smoke and require constant attention.

65 Having thus described my invention,

what I claim as new and desire to secure by Letters Patent, is:—

1. A structure of the character described comprising a series of alternate upper and lower decks, the upper decks being spaced 70 above the lower decks and adapted each to overhang the side edges of the two adjacent lower decks and protect the lateral light and ventilation openings formed between the decks, cantaliver means to support the 75 lower decks and beams passing above the lower and serving to tie the upper decks together.

2. A train shed for protecting tracks and their platforms comprising lower decks parallel with and adapted to cover the track platforms, and upper decks supported above the lower decks and disposed so as to cover the space between the lower decks and provide longitudinal protected light and ventilation openings between them and the lower decks. 80

3. A train shed comprising a series of spaced lower decks, supports therefor, and an upper deck supported by each pair of adjacent lower decks so as to cover the open space between them, said upper deck having its side edges overhanging the adjacent side edges of its supporting lower decks and spaced 90 above the same to provide a pair of longitudinal protected apertures for the purposes described. 95

4. A structure of the character described comprising a series of alternate upper and lower overlapping decks, means to support 100 said lower decks near their centers, and means to support the upper decks from the side edges of said lower decks above the latter.

5. In a structure of the character described, a series of spaced lower decks, upper decks supported by said lower decks so as to cover the open spaces between them, beams to support said lower decks which also serve as cantalivers to partly support the two adjacent upper decks on each side thereof, and means to support said beams. 110

6. A train shed comprising a series of lower decks which protect the platforms between tracks, a series of upper decks which 115 protect the tracks and overhang the edges of adjacent lower decks, leaving protected lateral apertures between the upper and lower decks, said upper decks having inclined underfaces which serve to deflect smoke towards said apertures. 120

7. A train shed comprising a series of platform decks lower at their side edges than the top of locomotive stacks, a series of track decks spaced above said platform decks so as to leave lateral protected apertures for light and ventilation, and deflecting surfaces under said track decks to direct the smoke to said apertures. 125

8. A train shed erected on the unit prin- 130

5 ciple and comprising alternate lower or platform decks and upper or track decks, the latter being supported by the former, and means to independently support each lower 5 deck, each pair of lower decks and the superimposed upper deck forming a unit portion of the shed independent of the rest thereof.

10 9. In a train shed covering a plurality of platforms, tracks between platforms, decks 10 to protect said platforms and which have their side edges disposed below the point of discharge of smoke from locomotives, means to prevent said decks draining onto said tracks, and means to cover the open spaces 15 between said decks.

15 10. A train shed structure of reinforced concrete and comprising a series of lower decks formed of concrete supported by central columns and beams, upper decks also 20 formed of concrete and supported by said lower beams as cantalivers and adapted to overhang said lower decks to form protected light and ventilation openings, said upper decks being formed in cross section so as to 25 deflect the smoke towards said openings.

20 11. A train shed comprising alternate upper and lower decks formed of thin reinforced concrete, supports for the lower decks comprising cross beams of heavily reinforced 25 concrete, concrete supports for the upper decks which rest upon the ends of said cross beams, conduits to drain the water from the

upper decks to the lower decks which are formed in said concrete supports, drainage conduits for the lower decks leading downwardly therethrough and through their supports, and a drain parallel with each lower deck to receive water from said pipes. 35

12. A structure of the character described comprising lower decks of thin reinforced concrete, means to support said sheds comprising thick reinforced concrete cantaliver beams, upper decks also of concrete, arch beams of reinforced concrete which support said upper decks and rest each upon the adjacent ends of two oppositely disposed cantaliver beams, and side walls extending upwardly from said lower decks, said decks being arched between supporting beams. 40

13. A structure of the character described comprising as a unit thereof a lower train deck, cantaliver supporting means therefor, a pair of upper decks supported at one side by the said lower deck and partially overhanging the same, said upper decks being 45 tied together by cross beams, substantially as described. 50

In testimony whereof I have hereunto set my hand in presence of two subscribing witnesses.
